UNITED STATES PATENT OFFICE

144,724

DESIGN FOR A DOLL

Ann J. Lorenzen, Atlantic City, N. J.

Application February 4, 1946, Serial No. 126,242

Term of patent 14 years

(Cl. D34—4)

To all whom it may concern:

Be it known that I, Ann J. Lorenzen, a citizen of the United States, residing at Atlantic City, in the county of Atlantic and State of New Jersey, have invented a new, original, and ornamental Design for a Doll, of which the following is a specification, reference being had to the accompanying drawing, forming part thereof.

In the drawing,

Fig. 1 is a front elevational view of a doll showing my new design;

Fig. 2 is a side elevational view thereof; and
Fig. 3 is the rear view thereof.

I claim:

The ornamental design for a doll, as shown.
ANN J. LORENZEN.
